(57) **CLAIM**

The ornamental design for a control handle for a material handling vehicle, as shown and described.

DESCRIPTION

In a preferred embodiment, the nature of this product is as a handle useful for controlling a material handling vehicle. FIG. 1 is a top, left, front perspective view of a control handle for a material handling vehicle embodying our new design;

FIG. 2 is a front elevational view thereof;

FIG. 3 is a top plan view thereof;

FIG. 4 is a rear elevational view thereof; and,

FIG. 5 is a left side elevational view thereof.

The broken line representations of portions of a material handling vehicle and control handle in FIGS. 1-5, are for the purpose of illustration only, and form no part of the claimed design.
